UNITED STATES PATENT OFFICE.

JAMES COOMBER, OF CHICAGO, ILLINOIS, ASSIGNOR OF ONE-HALF TO
FREDERICK A. HASTINGS, OF SAME PLACE.

LEMON-SQUEEZER.

SPECIFICATION forming part of Letters Patent No. 669,954, dated March 12, 1901.

Application filed December 21, 1898. Renewed March 23, 1900. Serial No. 9,963. (No model.)

To all whom it may concern:

Be it known that I, JAMES COOMBER, a citizen of the United States, residing at Chicago, in the county of Cook and State of Illinois, have invented certain new and useful Improvements in Lemon-Squeezers, of which the following is a full, clear, and exact description.

The present invention relates to lemon-squeezers, and more particularly to that class which may be conveniently secured to a counter, table, or shelf; and the object of the invention is to provide a construction which is simple, efficient, and may be quickly operated.

The invention consists in the several novel features of construction hereinafter described, illustrated in the accompanying drawings, and more particularly defined by claims at the conclusion hereof.

In the drawings, Figure 1 is a view in front elevation of a lemon-squeezer embodying the invention. Fig. 2 is a plan view. Fig. 3 is an end elevation. Fig. 4 is a view in vertical longitudinal section on line 4 4 of Fig. 2. Fig. 5 is an end view, the bracket for sustaining the receptacle for the juice being shown in section. Fig. 6 is a perspective of the bracket, and Fig. 7 is a perspective of a corner thereof.

A denotes a supporting-frame having an arm *a* extended downwardly therefrom. The supporting-frame A is designed to rest upon a table or shelf, adjacent the edge thereof, and its arm *a* is projected laterally, as at *a'*, and is provided with a jam-screw B, having a thumb-piece *b* at its lower terminal and a washer *b'* at its upper terminal. Jam-screw B engages the under side of the table or shelf and secures the supporting-frame A to the table or shelf.

C denotes a holder or cup in which the lemon from which the juice is to be extracted is placed. The holder is provided with an ear *c* at the back thereof, which is pivotally secured by a pin or rivet *c'* to a lug *a''* on the supporting-frame. The under side of ear *c* rests, as at *c''*, upon the supporting-frame A to restrict the movement of the holder C about its pivot and retain it opposite and aligned with a follower D. An arm *a''* is extended

from the supporting-frame, and against this arm the holder will abut when pressure is exerted against the holder C by the follower D. Arm *a''* relieves the pivot-pin *c'* of distorting strains. The holder is cut away or notched, as at *c''*, to afford an exit for the juice. Arms *a''* and *a'''* project forwardly from the supporting-frame and have mounted therein a shaft E, to the inner end of which a follower D is rigidly secured. The follower D is provided with a cone *d*, which is adapted to enter the holder, and a rim or annular flange *d'*, as well understood in the art.

A cam F and lever G, preferably formed integral, are secured to the follower-shaft between the arms or bearings *a''* and *a'''* by a pin *f*. Cam F serves to effect the axial shift of the follower-shaft, and lever G serves to impart rotation to the shaft, and being conjointly shifted the lever and cam effect a gyrating movement of the shaft E and follower D. The cam F comprises a hub *f'*, a spiral cam edge *f''* for advancing the follower, and a spiral cam edge *f'''* for retracting the follower. Cam edges *f''* and *f'''* are designed to engage, respectively, arms *a''* and *a'''* of the supporting-frame. Arm *a''* is provided with a friction-roller *a''''*, against which cam edge *f''* will impinge when the lever G is operated to advance the follower. Cam edge *f'''* engages arm *a''*, as at *a''''*, when the lever is shifted to retract the follower. Lever G projects normally rearward from the supporting-frame and is provided with a handle *g*. A shoulder *f''''* on cam F engages arm *a''* of supporting-frame A to retain the lever and handle normally within convenient reach of the operator.

A detachable shelf or bracket H, upon which a suitable tray or receptacle for receiving the juice may be placed, is supported in arm *a* of the supporting-frame below the holder and follower and in close proximity thereto. Shelf H is provided with guard-ribs *h* and *h'* and adjacent one of its corners with a dovetailed tongue or rib *h''*, which fits into a groove *a''''*, formed in arm *a* of the supporting-frame. Guard-rib *h'* terminates in a shoulder *h''''*, which engages the arm *a* and properly positions the shelf beneath the holder and follower.

In operation the holder is swung upwardly

and transversely to the position shown in dotted lines in Fig. 5, when a portion of a lemon-can is put therein and held until the holder is returned to its normal position alined with 5 the follower, when the projecting cone of the follower will hold the lemon within the holder. The handle g of lever G is then grasped by the operator and turned forwardly to rotate the follower-shaft. Such movement of the 10 lever causes cam edge f^2 to engage friction-roller a^6 and simultaneously advance the follower-shaft E and impart a gyrating movement to the follower and force the cone d thereof into the holder C , and thus firmly 15 compress the lemon in the holder. The juice escapes through notch c^4 into a receptacle on shelf H . As the lever G is returned to its normal position cam edge d^3 will engage arm a at a^7 and retract the cone d of the follower 20 from within the holder and permit the holder to be swung backwardly and the lemon to be removed from the holder.

It will be observed that the holder C is pivotally mounted in the supporting-frame and 25 arranged to be swung in a vertical transverse plane and at a right angle with the axis of the follower. This construction and arrangement is advantageous, because the holder can be located close to the follower-cone, so the 30 lemon when placed within the follower can be retained therein by the cone without first advancing the follower, inasmuch as the movement of the holder is in a plane parallel to the face of the portion of the lemon as usually cut, and, further, because the close arrangement of the holder and follower shortens the necessary axial shift of the follower.

The cam and lever afford means for shifting the follower, which can be quickly operated. A half-turn of the lever usually suffices to shift the follower sufficiently into the holder. Manifestly such mechanism can be much more quickly operated than the screw-shaft heretofore used and is more simple and 45 inexpensive of construction.

The purpose of providing a detachable shelf or bracket for sustaining the receptacle or tray (shown in dotted lines in Fig. 1) is to enable a tumbler of any size to be held close to the holder and follower when it is desired to 50 discharge the juice directly thereinto. It is customary to provide a tray to receive the juice when a large quantity is being extracted and when the operation is continuous. 55 The mouth of the receptacle must be close to the follower and holder, otherwise the spray would not pass into the receptacle. When it is desired to discharge the juice directly into a tumbler or receptacle other than the 60 tray, the shelf may be withdrawn from the grooves in the arm a of the supporting-frame, and a tumbler of any shape or size may be held in proper position below the holder and follower.

65 The supporting-frame, with its arm a , can be adjusted adjacent the edge of a table,

counter, or shelf of any thickness by jam-screw B and secured in position.

Manifestly the mechanism may be used for other analogous purposes, and the details of 70 construction may be varied without departing from the spirit of the invention.

Having thus described my invention, what I claim as new, and desire to secure by Letters Patent, is—

1. The combination with a supporting-frame, of a holder, a follower mounted in said frame and adapted to enter said holder, mechanism for advancing and retracting said follower, said holder having an ear at the back 80 thereof pivoted to the supporting-frame to swing said holder in a plane transverse to the axis of the follower, and an arm projected forwardly from the supporting-frame to form an end stop for the holder.

2. The combination with a supporting-frame, of a holder C , a follower adapted to enter said holder, mechanism for advancing and retracting said follower, said holder having an ear c at the back thereof resting on 90 said frame, and pivoted to a lug a^2 on the frame and an arm a^3 projected forwardly from the frame to form an end stop for the holder.

3. The combination with a supporting-frame, and a holder pivotally mounted thereon, of a follower adapted to enter said holder, a shaft mounted in bearings on projecting arms of said frame, a cam secured on said shaft and between said arms for axially advancing and retracting said shaft and having 100 edges to engage said arms and a lever for rotating said shaft.

4. The combination with a supporting-frame and holder, pivotally mounted thereon, of a follower adapted to enter said holder, a 105 shaft mounted in bearings projected forwardly from said frame, a cam secured on said shaft between said bearings for axially advancing and retracting said shaft, and having spiral edges to engage said bearings, 110 a friction-roller mounted in the bearing with which the cam edge for advancing the shaft engages and a lever secured to said cam for rotating said shaft.

5. The combination with a supporting-frame and holder pivotally mounted thereon, of a follower adapted to enter said holder, a shaft E mounted in arms or bearings a^4 and a^5 , a cam F secured to said shaft between 115 said bearings, spiral cam edges f^2 and f^3 engaging respectively a friction-roller a^6 and arm a^4 for axially advancing and retracting said shaft, a shoulder f^4 engaging arm a^5 and a lever G for rotating said shaft.

6. The combination with a supporting-frame, of a holder pivoted to said frame to swing in a plane transverse to the axis of the follower, a shaft mounted in bearings on arms projected forwardly from the frame, a follower secured to one end of said shaft, a cam secured to said shaft between its bearings and having edges engaging said arms, for axially 125

advancing and retracting said shaft, and a lever secured to said cam for rotating said shaft.

7. The combination with a supporting frame having a depending arm, a holder pivotally sustained on said frame, a follower, a shaft for said follower mounted in arms projected forwardly from said frame and mechanism for advancing and retracting said follower, of a detachable shelf having a tongue at one corner thereof secured in said depending arm.

8. The combination with a supporting frame, a holder pivotally sustained thereon, a follower mounted in said frame and mechanism for advancing and retracting said follower, of a shelf having at one corner thereof a tongue fitting into a groove in a depending

arm of the frame, and a shoulder engaging the said arm.

9. The combination with a supporting frame having a depending arm and extension and a jam-screw passing through said extension, of a holder pivoted to said frame, a follower adapted to enter said holder, a shaft mounted in bearings on arms projected forwardly from said frame and having the follower secured thereto, of a cam secured to said shaft between its bearings for advancing and retracting said shaft, engaging said arms, and a lever for rotating said shaft.
